UNITED STATES PATENT OFFICE.

HOWARD L. RULAND, OF CINCINNATI, OHIO.

HOSE-COUPING.

953,061.

Specification of Letters Patent. Patented Mar. 29, 1910.

Application filed October 25, 1909. Serial No. 524,557.

To all whom it may concern:

Be it known that I, HOWARD L. RULAND, a citizen of the United States, residing at Cincinnati, in the county of Hamilton and 5 State of Ohio, have invented certain new and useful Improvements in Hose-Couplings, of which the following is a specification.

My invention relates to pipe and hose connections, and has for its object the convenient and quick coupling of a hose, as is especially desirable in connection with the use 10 of fire fighting apparatus.

My invention consists in a stationary 15 spout and a collar to be applied thereto, hooks to hold the spout on the collar, and a cam to engage with the hooks and cause them to release the spout and collar from each other, as well as in the parts and in the 20 details of construction and arrangement of parts as will hereinafter be more fully described and claimed.

In the drawings: Figure 1 is a view, partly in longitudinal section and partly in 25 side elevation, of a device embodying my invention. Fig. 2 is a front elevation of the device, part of the casing being broken away to reveal the arrangement of the cam and other parts. Figs. 3 and 4, respectively, are 30 detail sectional side elevations corresponding to the view shown in Fig. 1, of the spout, and of the collar, detached. Fig. 5 is a detail, in diametrical section, of the cam. Fig. 6 is a rear elevation of the device. Fig. 7 is 35 a detail perspective view of one of the hooks.

The spout 1 has a rearwardly extending hub 1' provided with interior threads 1'', so that it may be screwed onto a water plug or other connection with which it is to be 40 used. This spout has another hub 1^a extending forward and tapering in that direction, with a conical outer surface 1^a', which is ground smooth to receive the corresponding inner surface of the collar 2. An exteriorly 45 extending annular flange 1^b comprises the middle part of the spout 1, and is provided with a series of slots 1^b', each of segmental shape, with its radial inner convex side 1^b'' sloped downward toward the front of the 50 spout.

The collar 2, above mentioned, comprises a forwardly extending hub 2^a tapering for-

wardly and having a conical inner surface 2^a', ground smooth, and with a series of external threads 2^a'' at its forward part. An 55 exteriorly extending annular flange 2^b forms the rearward part of this collar 2. This flange 2^b is provided with a series of openings 2^b', in number the same as the slots 1^b' in the flange 1^b of the spout, in the present 60 case four. These openings 2^b' are each just sufficient in width to admit the hooks 3 and allow them to have a certain amount of movement radially of the collar. These hooks extend rearwardly through these 65 openings and through the slots 1^b' of the spout, and engage radially inwardly with the flange 1^b of the spout, adjacent to the sloping sides of the slots 1^b'. The parts are so proportioned that when these hooks thus 70 engage the outer conical surface 1^a' of the hub 1^a of the spout and the inner conical surface 2^a' of the collar are in intimate contact throughout, so that, both of these surfaces being accurately finished, a water- 75 tight joint is formed.

The hooks 3 are pivoted to swing radially of the collar just forward of the openings 2^b', two lugs 3' being provided to flank each hook, with pins 3'' extending through the 80 hooks and lugs. Each hook has a forward extension 3^a, which, of course, when moved radially inward, causes the rearward part of the hook, or the hook proper, to move outward and be disengaged from the flange 1^b 85 of the spout. However, these hooks are caused to normally remain in engagement by means of springs 3^a' entering sockets 3^a'' in the extensions 3^a of the hooks, which springs are compressed against the adjacent 90 surface of the hub 2^a of the collar. Thus arranged, when the collar 2 is applied to the spout 1, bringing the conical surfaces together, the rearward ends of the hooks 3, which are tapered for this purpose, slide 95 out over the sloping surfaces of the sides 1^b'' of the slots 1^b', through these slots, and, when they have passed through, the springs 3^a' act to engage the hooks against the rearward side of the flange 1^b, as hereinbefore 100 described, whereupon the collar is held securely and firmly on the spout.

It will be seen that, each of the hooks being separately and independently pressed

into engaging position by its individual spring, the releasing of the collar from the spout requires that all the hooks be disengaged when the collar is being withdrawn. 5 To effect this simultaneous disengagement of all the hooks, a cam 4 is provided, comprising an annular shell 4' with a rearwardly and radially inwardly faced journal bearing 4" corresponding to a forwardly 10 and radially outwardly faced journal bearing 4''' on the flange 2^b of the collar. This shell 4' has, at its forward side, a series of radially inwardly extending segments 4^a, one being provided for each hook 3, and 15 each of these segments 4^a has its inner edge 4^{a'} eccentric to the rotation of the cam on its journal bearings above described, and is provided at each of its terminations with a lug or stop 4^{a''}. These segments are so spaced 20 around the cam, and are so proportioned, that each one of them will embrace the forward extension 3^a of one of the hooks 3 between its lugs or stops 4^{a''} and allow a certain amount of rotation of the cam on its 25 journal bearings before engaging either of the lugs or stops 4^{a''} with a side of the extension 3^a of the hook. At the same time the radially outwardly presented side 3^{a'''} of the extension 3^a of each hook 3 is inclined 30 circumferentially of the device to correspond to the eccentric trend of the inner edge 4^{a'} of the adjacent segment 4^a, and comes in engagement therewith. These eccentric edges of the segments are so arranged that when 35 the cam 4, of which they form part, is in a certain position, the hooks will be allowed to remain in engagement with the flange 1^b of the spout, under the action of the springs 3^{a'}, but, when the cam is rotated to the extent allowed by the lugs or stops 4^{a''}, the 40 forward extensions 3^a of the hooks will all be pressed radially inward, simultaneously, against the action of the springs 3^{a'}, and the hooks disengaged from the flange 1^b of the 45 spout, allowing the collar to be withdrawn from the spout.

To form a cover for the cam and the hooks and their springs, as well as to hold the cam against displacement from its journal bearing forwardly, a casing 5 is provided, comprising a shell 5' open at its rear with internal threads 5" to screw onto external threads 5''' on the flange 2^b of the collar immediately outside and to the rear 55 of the journal bearing of the cam. The front of this shell 5' is provided with an annular inwardly extending flange 5^a of such extent that a circular opening 5^{a'} is left of just sufficient diameter to allow the 60 conical forward extension 2^a of the collar to extend through.

For turning the cam 4 it is provided with a handle 4^b which extends forward through

a segmental slot 4^{b'} in the casing 5, of sufficient length to allow the required rotation 65 of the cam. To resist the rotation of the cam for releasing the hooks 3, and to cause the cam to normally have the position for permitting the hooks to engage with the flange on the spout, a series of tension 70 springs 6 are provided interiorly of the cam, between it and the flange 2^b of the collar, these springs 6 extending substantially tangentially of the device, and each having one of its ends attached to a lug 6' on the cam, 75 and its other end attached to a lug 6'' on the flange 2^b of the collar. These springs 6 are so applied that rotation of the cam to release the hooks will stretch the springs, and as soon as the cam is released they will cause 80 it to return to the position in which it allows the hooks to engage; at the same time, the hooks, under the action of the springs 3^{a'}, will resume their engaging positions. The cams, as will be noted, allow the hooks 85 to yield when passing over the edges of the slots in the flange of the spout, so that the coupling of the device is accomplished without any attention other than to cause the hooks to enter the segmental slots in the 90 flange 1^b of the spout and shove the collar onto the spout, upon which the device is secured automatically. To facilitate the application of the collar to the spout, the segmental slots are made amply long, so that 95 the hooks 3 may enter without special care as to the position in which the collar is presented to the spout. The releasing of the device is conveniently accomplished by merely rotating the cam by means of the 100 handle 4^b, and withdrawing the collar from the spout.

To form a proper finish to the rear part of the device, the flange 2^b of the collar has a rearwardly projecting rim 2^{b''} which surrounds the flange 1^b of the spout when the 105 collar is secured on the spout.

The ease of application of my improved coupling renders it particularly suitable for use by fire departments for making the hose 110 connection to street water plugs, where prompt action is of the utmost importance, while the efficient joint formed thereby is adequate for the demands of the service, avoiding the trouble of leakage under high 115 pressure as completely as does the ordinary screw connection, which is only applied with considerable delay and requires the use of a wrench to apply it.

For use on water plugs, my improved device is designed with the view of leaving the spout 1 on the plug permanently, while the collar 2 is permanently attached to the hose. Besides this use, it will be noted that the coupling is equally applicable for connecting different sections of hose, and will 125

also be found useful in other systems where an efficient connection for carrying a fluid is desired to be made quickly and conveniently.

5 In view of the different adaptations to which my improved device is susceptible, it will be understood that considerable variation of minor details of construction and arrangement may occur without departure 10 from the scope and spirit of my invention.

Having fully described my invention, what I claim as new and desire to secure by Letters Patent is:

1. In a hose coupling, a spout comprising 15 a hub with a conical outer surface tapered forwardly and an exteriorly extending annular flange at its rear, a collar comprising a hub with a conical inner surface tapering forwardly and an outwardly extending annular flange at its rear, said conical surfaces of the spout and flange, respectively, being adapted to make intimate contact, and the flanges of said spout and collar, respectively, being adapted to come adjacent when the 20 conical surfaces make such contact, a series of hooks adjacent to the flanges and adapted to engage with one of the flanges to hold the spout and collar together, and a cam having a journal bearing with one of the flanges and 25 provided with segments with edges eccentric to its journal bearing and adapted to engage with said hooks, whereby, when said cam is rotated on its bearing the hooks are caused to disengage from the flange, and allow the collar to be withdrawn from the 30 spout, substantially as and for the purposes specified.

2. In a hose coupling, a spout comprising 35 a hub extending forwardly and an annular flange at its rear, a collar comprising a hub extending forwardly and an annular flange at its rear, the hubs being adapted to fit together and the flanges to come adjacent, a series of hooks adjacent to the flanges and 40 adapted to engage with one of the flanges and hold the spout and collar together, a cam having a journal bearing with one of the flanges and provided with segments with edges eccentric to its journal bearing and 45 adapted to engage with the hooks to disengage them from the flange, and a spring engaging with the cam and with one of said flanges, whereby it opposes movement of 50 the cam to act on the hooks, substantially 55 as and for the purposes specified.

3. In a hose coupling, a spout comprising 60 a hub extending forwardly and an annular flange at its rear, a collar comprising a hub extending forwardly and an annular flange at its rear, the hubs being adapted to fit together and the flanges to come adjacent, a series of hooks adjacent to the flanges and 65 adapted to engage with one of the flanges

and hold the spout and collar together, a cam having a journal bearing with one of the flanges and provided with segments with edges eccentric to its journal bearing and adapted to engage with the hooks to disengage them from the flange, and a spring engaging with the cam and with one of said flanges, a casing covering said cam, provided with a segmental opening, and a handle on said cam extending through said opening, substantially as and for the purposes specified.

4. In a hose coupling, a spout comprising a hub extending forwardly and an annular flange at its rear, a collar comprising a hub extending forwardly and an annular flange at its rear, the hubs being adapted to fit together and the flanges to come adjacent, a series of hooks adjacent to the flanges and adapted to engage with one of the flanges and hold the spout and collar together, a cam having a journal bearing with one of the flanges and provided with segments with edges eccentric to its journal bearing and adapted to engage with the hooks to disengage them from the flange, and a casing covering said cam, mounted on one of said flanges, and holding said cam upon its journal bearing, substantially as and for the purposes specified.

5. In a hose coupling, a spout comprising a hub with a conical outer surface tapered forwardly and an exteriorly extending annular flange at its rear provided with a series of segmental slots, a collar comprising a hub with a conical inner surface tapering forwardly, and an outwardly extending annular flange at its rear provided with a series of openings, said collar being adapted to engage its conical inner surface with the conical outer surface of the spout, and the flanges of the spout and collar being adapted to come adjacent when said conical surfaces make such contact, a series of hooks pivotally mounted on the collar forward of its flange and extending rearwardly through the openings in the flange, said hooks being adapted to swing radially outward to pass through the segmental slots in the flange on the spout, and to engage with said flange at the rear and adjacent to the radially inward sides of the slots in the flange on the spout, 110 said sides of the slots being sloped radially inward and forwardly for the engagement of said hooks whereby they are swung radially outward when passing through the slots, extensions on the hooks forward of their pivotal mountings, springs acting on said extensions to cause the hooks to engage with the rear of the flange on the spout, a cam surrounding the hooks and having a journal bearing with the flange on the collar, 120 segments extending radially inward on said

cam and having inner edges eccentric to the journal bearing of the cam, said edges being adapted to engage with the extensions of the hooks, whereby when the cam is rotated they will cause the hooks to disengage from the flange on the spout, springs engaging with the cam and with the flange on the collar, whereby they oppose the rotation of the cam to disengage the hooks, a casing

surrounding the cam and secured to the 10 flange on the collar, having a segmental slot in its forward side, and a handle on the cam extending through the slot, substantially as and for the purposes specified.

HOWARD L. RULAND.
